[57] CLAIM

The ornamental design for an organizer for pancake and compact makeup, as shown and described.

DESCRIPTION

FIG. 1 is a left-front isometric view of an organizer for pancake and compact makeup showing my new design;
FIG. 2 is a plan view thereof;
FIG. 3 is a front elevational view thereof;
FIG. 4 is a bottom view thereof;
FIG. 5 is a rear elevational view thereof;
FIG. 6 is a right side elevational view thereof;
FIG. 7 is a left side elevational view thereof; and
FIG. 8 is a section along line 8—8 of FIG. 1.
